UNITED STATES PATENT OFFICE.

JOHN HARRIS, OF CLEVELAND, OHIO.

BLOWPIPE.

Application filed February 1, 1923. Serial No. 616,285.

To all whom it may concern:

Be it known that I, JOHN HARRIS, a citizen of the United States, residing at Cleveland, in the county of Cuyahoga and

5 State of Ohio, have invented a certain new and useful Improvement in Blowpipes, of which the following is a full, clear, and exact description, reference being had to the accompanying drawings.

10 This invention relates to blow pipes, and has for its general object to improve the construction of the tips and the manner of securing the same to their respective blowpipe heads. Further and more detailed 15 objects of the invention will be set forth in connection with the description of the embodiment of my invention illustrated in the drawings hereof, wherein Fig. 1 represents a central sectional view through a 20 blowpipe having my invention applied thereto; Fig. 2 an elevation, and Fig. 3 a central sectional view, of the tip employed in such pipe; and Figs. 4 and 5 are sectional details corresponding respectively to the 25 lines 4—4 and 5—5 of Fig. 1.

Describing the various parts by reference characters, 1 denotes generally the head of a blowpipe, said head having an enlarged bore extending downwardly to the lower end 30 of the head from an annular shoulder 2. The lower portion of this bore is threaded, as indicated at 3, and the extreme lower end is unthreaded and outwardly and downwardly beveled, as shown at 4. The outside 35 of the lower end of the head is also threaded, as indicated at 5.

From the shoulder 2, a bore or passage 6 extends upwardly and communicates with a chamber 7 to which cutting oxygen is 40 supplied by a branched passageway 8 and a tube 9. 10 denotes an inclined bore the upper portion of which is threaded for the reception of an injector 11, the lower end of the bore being contracted, as shown at 45 10^a, and discharging into the chamber 12 provided in the upper portion of the bore 8. The injector 11 is provided with a transverse portion 13 communicating with a passageway 14 to which preheating oxygen 50 is supplied by a tube 15, the port 13 communicating with a central passageway 13^a extending to the nozzle end of the injector. Communicating with the chamber 10^b surrounding the injector nozzle is a passageway 16 to which combustible gas is 55 supplied through a tube 17 having a nozzle 18 at its lower end a blow pipe being used

With the exception of certain details which cooperate with the tip (now to be described) the foregoing parts are such as are employed in a standard type of blowpipe designated and put into extensive use by myself.

The tip comprises generally an outer member 18 and an inner member 19, also of the same general type as employed by me in the aforesaid standard blowpipes, but with differences which will be pointed out as the description proceeds.

The outer member has a cylindrical upper portion and a tapered lower end 70 portion 18^a. Instead of being plain (as heretofore), the upper end is threaded, as shown at 18^b, to enable the tip as a whole to be screwed into the threaded lower end 3 of the head bore.

The inner tip member is provided with a long cylindrical upper portion 19^a and a short cylindrical portion 19^b adapted to fit closely within the cylindrical portion of the outer member; also a tapered or frusto-conical lower end portion 19^c adapted to fit closely within the tapered lower end of the outer member. Between the parts 19^a and 19^b, the inner member is provided with 80 opposed recesses 19^d, and the outer member is secured to the inner member by pressing corresponding portions 18^b thereof into said recesses, as set forth and claimed in my application No. 615,189, filed January 27, 1923.

The upper end of the part 19^a of the inner tip member preferably projects above the upper end of the outer member, and the parts 19^a, 19^b and the intermediate recessed portion are provided with external slots 95 providing passages 20 within the outer member for conducting the preheating mixture from the chamber 12 to the annular chamber 21, whence the mixture is conducted through the passages 22 to the delivery or working end of the tip. Above the part 19, the inner tip member is reduced, as shown at 19^e, and is provided at its upper end with a head 23 having a frusto-conical upper end 23^a adapted to seat against the circular inner edge of the shoulder 2 when the outer tip member is screwed home in the bottom of the head. The passage 24 100 for cutting oxygen extends centrally through the inner tip member and communicates with the passage 6 and chamber 7, and is supplied with oxygen from tube 15. The outer tip member is provided with a shoulder 25 which is seated in the head 23 when the outer tip member is screwed into the head 23.

25 denotes an upwardly and inwardly engaging parts (the cone ring) is adjustable. 5
25 denotes an upwardly and inwardly engaging parts (the cone ring) is adjustable. 10
slidably fitted upon the outer tip member and adapted to be forced into the tapered recess 4 and to be gripped against the said outer member by means of a gland nut 26 threaded on the lower end of the head and having an inwardly directed annular shoulder 27 surrounding the outer tip member. 15

Heretofore, I have connected tips and blowpipe heads of the type described herein by slipping the outer member into the lower end of the head and providing the upper 15
end of the inner member with a threaded head having a rounded upper end and the blowpipe head with a correspondingly-shaped threaded chamber below a bore corresponding in position to the bore or passage 6 herein. It has been found difficult 20
to obtain a proper seat for such rounded upper end of the tip head. The threads employed for connecting the tip to the blowpipe head were 27 to the inch, because 25
a coarser thread would reduce the size of the rounded head too much, with a corresponding reduction in the size of the central bore or passage 24. This small size of 30
thread made it difficult to cut the same accurately, and a slight variation or irregularity in the thread-cutting on the tip head or on the cup or recess therefor would result 35
in a leakage past the tip head. The present construction enables the use of a coarse 40
thread on the parts 3 and 18° (because of their size); and the head 23 may be provided with a straight taper (or frusto-conical surface) for the part 23a, enabling it to 45
take a line seat against the inner edge of the shoulder 2, the seat being of the needle-valve type. The accuracy of threading and the manner of seating the head 23 insures a 50
leak-proof joint between the parts 2 and 23a. 45

Should there be any slight eccentricity of 55
the inner tip member and the seat formed by the shoulder 2 (due to inaccuracy in machining the parts) the length of the part of said member which projects above the part 18° of the outer member will enable the head 50
23 to adjust and center itself with respect to its seat on the inner edge of said shoulder and thus provide a tight seat. 55

The recessing of the lower inner end of 55
the blowpipe head, as indicated at 4, allows the copper cone 4 to be moved along the outer member into said recess and, when the nut 26 is tightened, the tip as a whole is held firmly, and leak-proof connections are afforded, at two places, namely; where the 60
tapered end 23a engages the shoulder seat, and where the cone ring 25 engages the bottom of the head (in the recess 4). The cone-ring connection adapts itself for variations 65
that may exist in the distance between the seats at 2 and 3, as one of the two seat-

In my prior construction, it was necessary to use brass for the inner tip member because of the necessity for threading the 70 small head, corresponding to the head 23 herein, and to use fine threads thereon (for reasons hereinbefore set forth). By virtue of the construction herein, I am enabled to use copper for both members of the tip. 75
However, if brass be used for the inner member, its coefficient of expansion will cause the inner tip member to lengthen with respect to the outer member and the head and thus will insure a tight seat and a gas-tight closure between the parts 23a and 2. 80

Having thus described my invention, what I claim is:

1. In a blowpipe, the combination of a head having a passage for cutting oxygen and provided with an annular seat below such passage and a chamber below such seat, the lower end of the chamber being threaded and the lower end of the head surrounding such chamber being also threaded, a tip comprising an inner and an outer member, the outer member having a downwardly tapering bore at its lower end extending to the delivery end of the tip and the inner member having a downwardly tapering lower end fitting such tapered bore of the outer member, there being one or more passages for preheating mixture provided between such members and extending downwardly from the top of the outer member to the lower end of the tip, the inner member extending beyond and above the outer member and having a central passage for cutting oxygen and provided with a head having a tapered end adapted to engage the inner edge of said seat, the outer tip member being threaded into the lower end of said chamber, a gland nut threaded onto the lower end of the head and having an inwardly directed shoulder surrounding the outer tip member, and a packing ring on said shoulder engaging the joint between the outer tip member and the lower end of the head. 110

2. In a blowpipe, the combination of a head having a passage for cutting oxygen and provided with an annular seat below such seat, the lower end of the chamber being threaded, a tip comprising an outer member, and an inner member carried by the outer member, the outer member having its upper end threaded into the lower end of said chamber, there being one or more passages for preheating mixture extending downwardly to the lower end of the tip, the inner member being provided with a central passage for cutting oxygen and extending beyond and above the outer member and provided with a head having a ta- 115
120
125
130

pered surface adapted to engage the inner edge only of said seat, and means for packing the joint between the bottom of the chamber and the outer wall of the outer tip member.

3. In a blowpipe, the combination of a head having a passage for cutting oxygen and provided with an annular seat below such passage and a chamber below such seat, the lower end of the chamber being threaded, a tip comprising an outer member and an inner member carried by the outer member and extending substantially to the lower end of said outer member, the said tip having one or more passages for

preheating mixture provided between such members and extending downwardly from the top of the outer member to the lower end of the tip, the inner member being provided with a central passage for cutting 20 oxygen and extending beyond and above the outer member and provided with a tapered end portion adapted to engage the inner edge only of said seat, the top of the outer tip member being threaded into the lower 25 end of said chamber.

In testimony whereof I hereunto affix my signature.

JOHN HARRIS.
